UNITED STATES PATENT OFFICE.

JOSEPH W. HURD, OF ROCKFORD, ILLINOIS, ASSIGNOR TO THE ROCKFORD WATCH COMPANY, OF SAME PLACE.

STEM-WINDING WATCH.

SPECIFICATION forming part of Letters Patent No. 250,148, dated November 29, 1881.

Application filed March 21, 1881. (Model.)

To all whom it may concern:

Be it known that I, JOSEPH W. HURD, residing at Rockford, in the county of Winnebago and State of Illinois, and a citizen of the United States, have invented new and useful Improvements in Stem-Winding Watches, of which the following is a full description, reference being had to the accompanying drawings, in which—

10 Figure 1 is a view showing the pillar-plate and parts connected therewith, the small wheel which acts in setting the hands being disengaged from the train. Fig. 2 is a similar view, showing such setting-wheel engaged with the train. Fig. 3 is an edge view. The remaining figures, from 4 to 10, inclusive, are details.

The object of my invention is to provide simple and efficient means for setting the hands of a watch; and this object I accomplish by the mechanism illustrated in the accompanying drawings, which I will now proceed to describe in detail, afterward specifically pointing out the improvements in the claims.

25 In the drawings, A represents the pillar-plate.

a is a lever or bar pivoted to the pillar-plate at b; but between it and such plate there is room for wheels.

30 e is a small wheel upon the under side and inner end of the lever a.

d is a small wheel upon the pivot of the lever a, which wheel d engages with the wheel e.

e is a yoke pivoted upon the screw f.

35 h is a wheel at one end of this yoke, which wheel engages with the wheel d at all times. It also engages with the winding-wheel g when the parts are in the position shown in Fig. 1.

r is a lever which operates the yoke e. i is

40 a spring.

j is a small plate, having a hub, k, on the top thereof, and a flange, l, at right angles to such plate.

45 m is the winding-stem, which carries a pinion, n. The stem is inserted in a hole in the flange l and held therein by a screw on the inside of the flange, but so that the stem can rotate.

o is a wheel which is placed upon the hub k

50 on the plate j. The yoke e rests on the top of

this hub. The plate j and yoke e are both held in place by the screw f, and the wheel o is between the plate j and yoke e, and engages with the wheel h, which is carried by the yoke e.

55 In use the parts will ordinarily be in the position shown in Fig. 1, ready for winding, the wheel h being engaged with the winding-wheel g. In this position the hands cannot be set, because the wheel c is disengaged from the train.

By means of the lever r one end of the yoke e can be made to act upon the lever or bar a, bringing the parts into the position shown in Fig. 2, in which the wheel c will be engaged 65 with the wheel v, and by turning the stem m the hands can be set. On returning the lever r to its former position the action of the spring i will disengage the wheel e from v and cause the wheel h to engage with the winding-wheel g. 70

The plate j, with its hub and flange, furnish a very compact device, having two bearings, one for the pinion n in the flange, the other being the hub k, which receives the wheel o.

I do not limit myself to the exact devices 75 shown for operating the lever or arm a, as the same may be modified, both as to form and arrangement.

The wheel v engages with the cannon-pinion, which is not shown in the drawings. 80

What I claim as new, and desire to secure by Letters Patent, is as follows:

1. In a stem-winding watch, the combination of the pivoted swinging lever a, provided with the wheels d and e, which engage 85 each other, with the wheels v and g and the pivoted oscillating yoke e, provided with the wheels h, engaging the wheel d on the swinging lever, said members being organized for operation substantially as and for the purpose 90 described.

2. The plate j, provided with a hub, k, to receive the crown-wheel o, and a flange, l, forming a bearing for the winding pinion or stem of a stem-winding watch, substantially as and 95 for the purposes specified.

JOSEPH W. HURD.
